FISH LURE

Earl E. Miller, Knoxville, Tenn., assignor to
Brunswick Corporation, Skokie, Ill.

Filed Oct. 22, 1971, Ser. No. 192,722

Term of patent 14 years

Int. Cl. D22—05

U.S. Cl. D22—27

FIG. 1 is a side elevation of a fish lure, showing my new design;

FIG. 2 is a top plan view thereof;

FIG. 3 is a front elevation thereof.

The broken lines in FIG. 1 are for illustrative purposes only.

The sides opposite those in FIGS. 1 and 2 are similar, it being understood that a portion of the fish scale ornamentation at the center of the body has been omitted for convenience of illustration.

I claim:

The ornamental design for a fish lure, substantially as shown and described.
